UNITED STATES PATENT OFFICE.

JACQUES SAOUTCHIK, OF NEUILLY-SUR-SEINE, FRANCE.

DEVICE FOR RAISING OR LOWERING WINDOW PANES.

Application filed July 7, 1926. Serial No. 120,977.

This invention relates to devices for raising or lowering sliding window panes on motor cars or other vehicles of the type comprising racks arranged laterally of the pane 5 frame and toothed pinions carried by the supporting frame and gearing with the racks under the actuation of a handle positioned intermediate the ends of said supporting frame, independent latches being associated 10 with said frame and racks for securely locking the pane at any desired height and for thus precluding any "creeping" thereof.

The primary object of the invention is to provide a device of the aforesaid type having 15 an improved rack and pinion structure whereby the operative engagement of the pane frame and window or door supporting frame is rendered more efficient and consequently the raising or lowering of the former 20 slidably to the latter more secure and progressive.

A further object of the invention is to provide a device of the aforesaid type having improved actuating means associated with 25 the handle or knob whereby the raising of the pane frame is rendered easier and less tiresome particularly in the case of large and heavy frames.

A still further object of the invention is 30 to provide a device of the aforesaid type having improved means for locking the pane frame at the desired height more easily i. e. by means of a smaller strain and thus to preclude any "creeping" thereof.

Other objects and advantages of the invention will incidentally appear from the following description reference being had to the accompanying drawings wherein:—

Figure 1 is a fragmentary perspective view 40 of the improved device showing the pane frame unit slidably mounted upon a stationary window pane.

Figure 2 is a detail view of a train of gears associated with the actuating members.

Figure 3 is a fragmentary perspective view 45 of the pane frame showing the part of the improved locking means to which are imparted the operating stresses.

Figure 4 is another fragmentary perspective view 50 of the pane frame showing the operative association of its actuating pinion with the rack of the slidable pane frame.

Figure 5 is another fragmentary perspective view showing in detail the part of the 55 improved locking means associated with the rack on the slidable pane frame.

Reference being had to these several figures wherein like references designate like parts, it must first be understood that the expressions "outer" and "inner" which will be 60 found in the following description particularly as applying to the slideable pane frame must be construed as corresponding to an observer who would view the device respectively from without and from within the car. 65

The improved device is readily applicable to all windows or doors of motor cars or other vehicles fitted with vertically adjustable panes and will find a special utility in connection with large-sized panes such as the 70 pane of the window surmounting the partition between the drivers' seat and the inside seats in "coupé" cars, "landaulet" cars or the like.

According to the invention, the device 75 comprises two distinct parts. The first part A of stationary structure is formed by an elongated metal framework (made of cast aluminum alloy for instance, adapted to be firmly secured by any suitable fastening 80 means to the body of the car adjacent the window or door opening which is substantially equals in length so as to have its top edge flush with the lower edge of said opening by being concealed in the corresponding plain or upholstered part of the body. The second part B of movable structure is formed by a metal frame comprising two upstanding legs *b* united intermediate their ends and at their upper ends by two cross beams *b*¹, *b*² so 85 as to properly carry the glass pane P therebetween. As will be more fully described hereinafter, the movable part B is slidably supported by the stationary part A so as to cause the pane P to be vertically shifted 90 with respect to said stationary part A i. e. to the body of the car in which the latter is embedded.

Each of the upstanding legs *b* of the movable part B has fixed against its outer edge 100 by any suitable fastening means such as screws 2 or integrally formed therewith a rack 1 the teeth of which are turned inwards.

The legs *b* are grooved throughout their length and united by two grooved cross beams: a lower cross beam *b*¹ perpendicular thereto and an upper cross beam *b*² conveniently of such a shape (a convex shape for instance) as to fit the upper edge of the window or door opening. Within the 105 grooves formed in said legs and cross beams is set a glass pane P.

The stationary part A is substantially formed of a built-up metal beam reinforced by struts *a*. Both ends of the struttied beam are enlarged into shoulders which present two hollow portions: an inwardly directed narrow groove *a*¹ the purpose of which will appear hereafter and a broader side groove *a*² adapted to snugly embrace the upstanding leg *b* and the contiguous rack 1 (see Fig. 4) whereby the movable part B is slidably supported in the stationary part A. Longitudinally extending throughout the latter somewhat to the rear of its inner face as shown in Fig. 3 is a shaft 3 rotatably carried by bearing blocks *d* and provided intermediate its ends, preferably midway of its length, with a bevel pinion 4 meshing with a bevel wheel 5 fast upon a spindle 6' which projects at right angles to the beam A in a suitable casing C formed integral therewith or fixed thereto. Said casing C has outer radial stiffening ribs *r* and in its inner capacity is housed a suitably reckoned reducing gear preferably composed of three (or another odd number) intermeshing pinions 6, 7, 8 respectively mounted upon spindles 6', 7', 8' as diagrammatically shown in Figure 2, the spindle 8' being extended to such an extent as is governed by the very thickness of the plain or upholstered part of the car body to carry a crank and a handle H or alternatively a knob of more or less decorated structure. Around the spindle 6' is coiled a spring of known construction (not shown) housed in the casing C and adapted to exert a braking effect on the reverse rotation of said spindle 6'. Adjacent each end of the shaft 3 rotatably carried in a lug 9 is rigidly mounted a pinion 10 so positioned as to continuously mesh with the respective rack 1. By this arrangement, it will be readily understood that by turning in the proper direction the handle H both pinions 10 will be caused to rotate and thus to move the racks 1 upwards thereby raising the pane frame B.

Longitudinally extending throughout the beam A somewhat rearwardly of its inner face as shown in Fig. 3 and parallel to the actuating shaft 3 is another shaft 11 rotatably carried in a pair of slightly spaced bearing blocks *e*. Upon the portion of the shaft 11 intermediate said bearing blocks *e* is rigidly mounted a pinion 12 which meshes with an adjacent rack 13 slidably carried by a bracket *f* suitably fixed to the beam A or formed integral therewith so as to inwardly project from said beam to such an extent as is governed by the thickness of the plain or upholstered part of the car body. The inner end of the bracket *f* has a boss *f*¹ through which freely passes a spindle 14 rigidly carrying a pinion 15 meshing with the rack 13 and extended at one end into an enlarged head 14' to which is suit-

ably attached an inwardly projecting lever 16 the purpose of which will presently appear. At its opposite end protruding from the boss *f*¹, the spindle 14 has coiled thereon a small spring 17 abutting against a pin 17' so as to hold the rack 13 and pinion 15 in mesh. Each end of the shaft 11 is rigidly fitted with a cam 18 adapted to engage an upstanding lever 19 pivotally mounted upon a pin 20 and having its upper end fitted with an elbowed member 21 suitably fixed thereto as by screws 21' or formed integral therewith the free straight end of which is provided with teeth of a pitch equal to that of the teeth of the rack 1 whereby said member 21 is adapted to act as a locking claw by intermeshing with the rack. The upstanding lever 19 is pivotally housed in the narrow groove *a*¹ formed in the end of the beam A and submitted to the antagonistic action of a plurality of strong springs 22.

By this arrangement, it will be understood that whilst normally, due to the action of the springs 22, the levers 19 hold the claws 21 in locking engagement with the racks 1 thereby invariably maintaining the pane frame B at any desired height whilst absolutely precluding any "creeping" thereof, it is possible at any time to readily unlock the racks 1 and the frame B to which they are secured by clearing the claws 21 off therefrom by means of the aforesaid cam actuating device. All that is necessary for that purpose is to angularly displace the lever 16 which to that effect is suitably shaped and placed in the car within easy reach of the passengers, thereby causing the shaft 11 to be rotated through the intermediary of the pinions 12, 15 and rack 13 and both cams 18 to swing the upper ends of the levers 19 and consequently the claws 21 away from the racks 1.

As will be appreciated the respective size of the pinions 12 and 15 and the length of the actuating lever 16 will be so calculated as to provide a sufficient leverage for permitting the resistance of the several springs 22 normally holding the claws 21 in locking engagement with the racks 1 to be readily overcome merely by exerting a relatively small stress such as the one a lady passenger for example can exert. The return of the levers 19 and the claws 21 to locking engagement with the racks 1 and the concomitant stopping of the sliding motion of the pane frame B will automatically take place under the action of the springs 22 as soon as the actuating lever 16 will be moved back to locking position.

It will be readily understood that this device for raising or lowering window panes being made up of a relatively small number of strong and easily mountable parts of small volume and not liable to get out of order will operate very satisfactorily in all

circumstances. Moreover although its construction as has just been described is deemed to be the simplest and most efficient one in practice, yet it must be understood that several constructional modifications might be introduced therein particularly for appropriating same to the several types of motor car windows or doors or even to architectural purposes without departing from the spirit and scope of the invention.

What I claim and desire to secure by Letters Patent is:—

1. A raising and lowering device for window and like panes, comprising independent end members of channel form in cross section and an intermediate connecting member of channel form in cross section and fitted within the channel formation of the end members, each of the end members being integrally formed with a channel offset from the longitudinal plane of the member and opening inwardly toward the member to slidably receive a pane-carrying frame, the end members being further formed with an integral channel arranged in the longitudinal plane of the member and opening at right angles to said plane, said latter channel serving to house an operating means and a locking means for the pane frame.
2. A raising and lowering device for window panes and the like, comprising end sections of channel formation and an intermediate section of channel formation fitting within and maintaining desired spaced relation of the end sections, each end section being formed with a channel opening toward the intermediate section and offset from the plane of the end section and with a further channel arranged in the plane of the end section and opening in a direction at right angles thereto, a window pane frame slidably mounted in the first mentioned channel, a rack secured to the window pane frame with the teeth extending toward the second channel, operating means arranged in the second channel to cooperate with said teeth for raising and lowering the frame, actuating mechanism carried by the intermediate section, and connections between the actuating mechanism and operating means.
3. A raising and lowering device for window panes and the like, comprising end sections of channel formation and an intermediate section of channel formation fitting within and maintaining desired spaced relation of the end sections, each end section being formed with a channel opening toward the intermediate section and offset from the plane of the end section and with a further channel arranged in the plane of the end section and opening in a direction at right angles thereto, a window pane frame slidably mounted in the first mentioned channel, a rack secured to the window pane frame with the teeth extending toward the second channel, and operating means arranged in the second channel to cooperate with said teeth for raising and lowering the frame.

3. A raising and lowering device for window panes and the like, comprising end sections of channel formation and an intermediate section of channel formation fitting within and maintaining desired spaced relation of the end sections, each end section being formed with a channel opening toward the intermediate section and offset from the plane of the end section and with a further channel arranged in the plane of the end section and opening in a direction at right angles thereto, a window pane frame slidably mounted in the first mentioned channel, a rack secured to the window pane frame with the teeth extending toward the second channel, and operating means arranged in the second channel to cooperate with said teeth for raising and lowering the frame.

dow panes and the like, comprising end sections of channel formation and an intermediate section of channel formation fitting within and maintaining desired spaced relation of the end sections, each end section being formed with a channel opening toward the intermediate section and offset from the plane of the end section and with a further channel arranged in the plane of the end section and opening in a direction at right angles thereto, a window pane frame slidably mounted in the first mentioned channel, a rack secured to the window pane frame with the teeth extending toward the second channel, operating means arranged in the second channel to cooperate with said teeth for raising and lowering the frame, actuating mechanism carried by the intermediate section, and connections between the actuating mechanism and operating means.

4. A raising and lowering device for window panes and the like, comprising end sections of channel formation and an intermediate section of channel formation fitting within and maintaining desired spaced relation of the end sections, each end section being formed with a channel opening toward the intermediate section and offset from the plane of the end section and with a further channel arranged in the plane of the end section and opening in a direction at right angles thereto, a window pane frame slidably mounted in the first mentioned channel, a rack secured to the window pane frame with the teeth extending toward the second channel, operating means arranged in the second channel to cooperate with said teeth for raising and lowering the frame, actuating mechanism carried by the intermediate section, and connections between the actuating mechanism and operating means, said connections being housed within the channel formation of the intermediate and end sections.

In testimony whereof I have signed my name to this specification.

JACQUES SAOUTCHIK.
